KNOB

Adolf Gottwald, Iserlohn, Germany, assignor to Friedrich Grohe, Hemer, Germany, a firm

Filed Mar. 13, 1970, Ser. No. 21,897

Term of patent 14 years

Int. Cl. D8—03

U.S. Cl. D8—145

FIG. 2

FIG. 1

FIG. 3

FIG. 4

FIG. 1 is a perspective front view of the knob, showing my new design;

FIG. 2 is a side view;

FIG. 3 is a top view; and

FIG. 4 is a bottom view of this knob.

The side view of this knob not shown in the drawing has an appearance identical with the appearance of the side view shown in FIG. 2 of the drawing.

I claim:

The ornamental design for a knob, substantially as shown and described.
